METHOD OF AND MEANS FOR CONTROLLING THE OPERATION OF HEAT EXCHANGE DEVICES

Philipp Borchardt and Hans Ranke, Solln, near Munich, Germany, assignors, by mesne assignments, to Union Carbide and Carbon Corporation, a corporation of New York

Application January 9, 1934, Serial No. 705,976
In Germany January 17, 1933

17 Claims. (Cl. 62—175.5)

The present invention relates to control methods and systems, and particularly to such methods and systems in which the volume of a gaseous fluid flowing through, or discharged by, a plurality of receptacles or heat exchange devices is controlled by the temperature of the gaseous fluid. In the separation of gas mixtures into their components by liquefaction it is customary to use heat exchange devices or regenerators in order to make the heat exchange between the incoming fresh gas and the products of the separation as perfect as possible. A satisfactory heat exchange, however, is possible only if the heat content which the fresh gas gives up to the regenerator in the state of equilibrium is exactly equal to that which is required by the separation product to heat it to the temperature at which the fresh gas enters the heat exchange device, that is, if the difference in heat content for both gases at both ends of the device is exactly the same. Furthermore, in gas separation plants a number of such devices or regenerators are necessary; in the separation of air, for example, two are needed for oxygen and two for nitrogen. The problem, therefore, is to distribute the fresh gas and the separation products among the individual regenerators in such a way that the above condition is complied with for each individual regenerator.

If the heat exchange is accomplished in so-called counter-current coolers, such a distribution of the gas quantities is likewise necessary; however, in this case no difficulties are presented because the heat capacity of the counter-current cooler is so low in relation to the heat capacity of the gases flowing therethrough, that when the volumes of gas flowing therethrough are varied, the new permanent state of equilibrium is attained in a short period of time. It is therefore sufficient to control the discharge temperature of the separation products coming out of the heat exchange device, whereby each error in distribution becomes immediately noticeable through the decrease of the discharge temperature of one gas in comparison to that of the other. No difficulties are thus presented in carrying out the distribution in such a manner that the difference in heat content of the outgoing separation products as against the incoming fresh gas is maintained at a minimum.

When using heat exchange devices such as regenerators, if a change is made in the volume of the gas flowing therethrough, the new state of equilibrium is attained only after a relatively long time, often not for several hours. The control

method used for counter-current coolers is therefore impracticable, and it appears to be impossible, for example, to correctly distribute the incoming gas to four regenerators operating in parallel, and to simultaneously benefit, in a practical manner, from the advantages which are theoretically offered by the use of regenerators.

The present invention makes it possible to overcome this difficulty and to correct unbalances or errors in distribution automatically and immediately, regardless of the length of the adjusting period of the regenerators taken as a whole.

The invention is based upon the observation that even when utilizing exceedingly large storing devices or regenerators, the temperatures at the cold end of a regenerator vary in a relatively close manner with the changes in the gas volumes flowing therethrough. These temperatures, and especially the temperature difference between the incoming gas and the products of the separation, do not remain constant during any one period of flow in one direction, but rather change continuously, particularly towards the end of a period; their course during a double period to a certain degree resembles a hysteresis-loop. The temperature difference between fresh gas and separation product at the end of a warming period, however, is largely dependent upon whether the separation product in the previous period yielded too much or too little cold content to the regenerators. This invention contemplates taking advantage of the difference in temperature existing between the gas mixture which is to be separated on the one hand, and the separated gases on the other hand, as measured at the cold end of the regenerators, toward the end of a period of flow in one direction, for the purpose of automatically controlling the volumes of gas passing through the regenerator. This may be accomplished, for example, by means of temperature responsive devices, such as thermometers which are located in the gas ducts, and other suitable control devices.

One particular embodiment of this invention will now be described in connection with the accompanying drawings in which:

Fig. 1 represents a schematic diagram showing the temperature variations at the cold end of a regenerator in operation as a heat exchange device between oxygen and air in the liquefaction of air;

Fig. 2 shows a schematic diagram of an air separating plant including regenerators and switching apparatus for the automatic distribution of the incoming air to the various regenerators; and

50

55

Fig. 3 illustrates diagrammatically in more detail an electrical switching apparatus suitable for determining the mean value of the individual temperature measurements recorded for the various regenerators which are shown in Fig. 2.

Referring more particularly to Fig. 1 the curves shown represent the temperature variations at the cold end of a regenerator in operation as a heat exchange device between oxygen and air, as a function of time during a period of gas flow in one direction. The ordinate indicates the temperature in degrees centigrade absolute, and the abscissa the time in minutes. The oxygen flowing into the regenerator during a period of flow in one direction has a substantially constant temperature which is approximately its temperature of evaporation. Following the reversal of gas flow, the compressed air which flows through the regenerator in the opposite direction initially is cooled to the same temperature as the oxygen, except for the slight difference caused by the losses incurred during the heat transfer from the gas to the gratings of the regenerator and thence back again to the gas. However, towards the end of the period of flow in one direction the temperature of the air rises steadily because the temperature of the regenerator increases. If the air volume is correctly regulated with respect to the separated gas, the temperature of the air will, for example, follow the course shown in the diagram by the solid line. The rise in temperature towards the end of the period of flow in one direction is caused by the unavoidable difference in heat content between the compressed air and the expanded separated gas. If too much air flows through the regenerator in relation to the volume of the separated gas, then the temperature of the air will rise much higher in the second half of the period, especially towards the end, as shown in the upper broken line. If the air volume is too small, then the temperature of the air towards the end of the reversal period will remain close to that of the separation product. If, towards the end of a reversal period, a regenerator supplies to the separation plant, air which is too hot, then the impurities in the air, such as carbon dioxide and nitrous oxide, which are desired to be reversibly retained in the regenerators, will only be partially separated and will consequently reach the separation apparatus, in which they will accumulate and thus cause serious difficulties.

Referring now more particularly to Fig. 2 of the drawings, a two-stage air rectifying apparatus is shown at 5. The nitrogen discharged at 6 yields its cold content to the pair of regenerators 1, 2 in heat exchange relation with the major portion of the air, while the oxygen leaving the separating apparatus at 7 yields its cold content, in the regenerator-pair 3, 4, to the remainder of the air to be separated. At the cold end of the regenerators at 11, 12, 13 and 14, temperature indicating devices, such as thermometers are located in the various ducts. Use may be made, for example, of resistance thermometers, whose time-lag is so low that they readily follow the fluctuations of the temperatures during each period of reversal. The resistance thermometers 11 and 12 are connected to constitute two branches of a Wheatstone bridge circuit, the thermometers 13 and 14 forming the corresponding branches of a second bridge circuit. A so-called drop-bail instrument 16 is utilized as zero instrument in the bridges, which is so adjusted that the bails are depressed at the end of each regenerator period and approximately 10 to 20 seconds before the re-

versal of the regenerators. This instrument is described in detail on pages 96, 97 and 98 of a publication entitled "Der Chemie-Ingenieur", vol. 2, part I, 1932. The bridge circuit and the sensitivity of the instrument are preferably so adjusted that the instrument closes a circuit when the temperature difference between air and separation products exceeds or falls below a certain temperature range. If, for example, the temperature difference between air and separation product amounts to 6° when the valve adjustment of the regenerators is correct, then, the bridge apparatus is so adjusted that the drop-bail instrument closes a circuit when the temperature difference amounts to less than 4° or more than 8°. The instrument regulates throttle valves 21, 22, 23 and 24 located in and controlling the air supply lines through which the air flows to each regenerator. The instrument accomplishes this through the agency of the switching apparatus 15 and the system of relays to be described herein-after, in such a way that the air supply is reduced when the temperature difference exceeds 8°, and is increased when the temperature difference falls below 6°. The reversal of the regenerators is accomplished by the periodic operation of the reversal valves 21', 22', 23' and 24' located in the conduits between the throttle valves 21, 22, 23 and 24 and the respective regenerators 1, 2, 3 and 4. The switching apparatus 15 also reverses the regenerators 1, 2, 3 and 4 after regular periods of time, e. g. by transmitting impulses to the reversing valves 21', 22', 23' and 24' at intervals of three minutes, in such a manner that for a period of three minutes nitrogen flows through regenerator 1 and air through regenerator 2, whereas for the next three minutes air flows through regenerator 1 and nitrogen through regenerator 2. In the same manner, oxygen and air are alternately caused to flow through regenerators 3 and 4. The switching apparatus 15 also connects the thermometers 11, 12, 13, 14 through lines 211, 212, 213, 214 to the control instrument 16 over line 35 one-half of a minute prior to the end of the cycle during which air flows through the respective regenerator. Thus, the thermometers transmit their measuring values successively to the drop-bail instrument 16. The contact bars of the instrument 16 are depressed a few seconds prior to the end of the cycle, and thus the relays 31—34, 41—44, 51—54 (Fig. 3) which are located in the relay box 17 are operated over lines 36, 37, 38 and 131—134, 141—144, 151—154 according to whether the temperature measurements at the respective thermometers exceed or are below a certain temperature range.

Each individual control operation changes the volume of the air so that the temperature difference between separation product and air at the cold end of the regenerator in the permanent state is changed a certain amount, for example, 2°. The time for attainment of the new permanent state following each regulation takes several reversal periods at the lower end of the regenerator also. If, therefore, a regulation was to be effected at the end of each regenerator period, an excess of control or over-regulation would result. This difficulty may be obviated either by effecting a control operation only at intervals of from five to ten reversals, or by providing a suitable feed-back or return impulse. The feed-back may preferably be accomplished by electrical means, in that simultaneously with the regulating operation, the bridge circuit is so adjusted

by the insertion or shunting of additional resistances, that the change in the temperature difference in the state of equilibrium corresponding to one operation has already progressed part way, 5 for example, to one-third. The feed-back impulse is or may be cancelled at the subsequent measurement of the temperature difference at the same regenerator, during which the drop-ball instrument remains in the rest position.

10 Only a single drop-ball instrument is required for connection with all of the regenerators. If the reversal period of a regenerator-pair, for example, amounts to three minutes, then the reversals of the two pairs are spaced one and one-half 15 minutes apart, so that a reversal occurs every minute and a half. By means of the time switch 15 the drop-ball instrument is switched into the proper bridge circuit approximately one minute before each reversal of the regenerators, and, for example, ten seconds before the regenerator-pair 20 is reversed, the bails or bars of the instrument are depressed, whereby that particular valve is actuated through which the air enters into the regenerator which is momentarily traversed by air. 25 One-half minute following the reversal, the drop-ball instrument is switched by the time switch into that bridge circuit which is connected to the regenerator to be reversed one and one-half minutes later.

30 The principle of the invention, that is, automatically controlling the gas volumes flowing through regenerators by means of the regenerator temperatures, can be applied in other ways than shown in the above embodiment. For example, 35 instead of the temperature difference between separation product and fresh gas, it is also possible to use a predetermined absolute temperature of the fresh gas at the cold end of the regenerator as a control. Another method of operation is 40 that the temperature difference between two regenerators of a pair is utilized for regulating the volumes. In this case the thermometers are preferably located in the cold half of the regenerators. Mechanical thermometers, such as metal 45 thermometers, gas thermometers, and vapor pressure thermometers may be used as temperature indicating devices; however, electrical thermometers (thermocouples or resistance thermometers) possess the advantage of direct electric 50 transmission.

The modification of the invention which has been described above is based on the assumption that the most favorable distribution of the air volumes to the various regenerators will result 55 in a certain difference in temperature between the fresh gas and the separation product at the cold end of the regenerators, a difference caused by the change in the heat contents with changes in pressure, as well as by the unavoidable losses 60 in refrigeration. Thus, a change in the volumes of gas flowing through the individual regenerators is produced when the temperature of the cooled air deviates from an assumed average or normal figure. This method entails the difficulty 65 that the adjustment to this normal figure for the temperature difference is impossible without arbitrary assumptions in regard to the heat exchange conditions in the regenerators, etc., and that even when the correct normal figure for 70 the temperature difference has been obtained, it is liable to be affected or varied by changes in the refrigerating conditions, etc. If, for example, the value of the assumed normal temperature difference is increased for any reason during 75 operation, the automatic regulation described

above will reduce the air supply to all regenerators, even though the distribution of the air to the various regenerators is correct. The only change resulting from this is that of the total volume of air discharged. However, inasmuch 5 as the volume of the separated components of the air is changed to the same extent, there is no change in the relation of the heat contents exchanged through the regenerators, so that this method does not compensate for any false 10 temperatures, but rather only disturbs the operation by detrimentally affecting the production. The control system described above is too sensitive because of its adjusting of the volumes of 15 fresh gas passing through a single regenerator without consideration of the fact that the total volume of fresh gas passing through the regenerators is predetermined or constant and by changing the volume of gas passing through one regenerator, the rate of flow through all the other 20 regenerators is necessarily affected. In order to obviate these difficulties, it is a further feature of this invention to measure and regulate the flow of gas through the various regenerators in 25 a manner which takes into consideration the mutual dependence of the individual regenerators in the distribution of the total volume of incoming gas. According to this feature of the invention, the distribution of the fresh gas volumes is accomplished in such a manner that 30 there is first obtained a mean or average value of the individual regulating measurements, and that then a change is made in the air supply of only those regenerators whose temperature 35 deviates from this mean value, so that the sum total of the absolute temperature differences of the individual regenerators as compared to the mean value of their temperatures tends to approach a minimum and to become zero in the most favorable case. Simultaneously therewith, 40 this mean value of the temperatures of the fresh gas at the cold end of the regenerators may be set to a certain value which may be considered the normal operating value. We shall assume 45 that air is to be distributed to the four regenerators of an air separation plant, two of which serve for exchanging the heat contents of the major portion of the air and the nitrogen, and the other two serve for the heat exchange between the remainder of the air and the oxygen. 50 The control measurements are effected with the aid of resistance thermometers a few seconds before the end of the period of flow in one direction. The absolute temperature of the air at the cold end of the regenerators is measured and the 55 measurements are transmitted to a Wheatstone bridge circuit, or preferably directly to a crossed-coil-drop-ball instrument. The mode of operation of a "crossed-coil" instrument has been described in a publication entitled: "Der Chemie— 60 Ingenieur" vol. 2, part I, 1932, on pages 54 and 55.

The impulses produced by the drop-ball instrument in accordance with the control measurements are not directly utilized for regulating 65 the throttle valves in the air supply lines to the regenerators, but their mean value is first determined by means of a switching or compensating apparatus, and a control operation is initiated only if the temperatures of the individual 70 regenerators deviate from this mean value.

The diagram of Fig. 3 illustrates schematically an apparatus 18 suitable for determining the mean value of the control measurements obtained for the four regenerators 1 to 4 as well as re- 75

lays 31 to 34, 41 to 44, 51 to 54 (these twelve relays correspond to box 17 of Fig. 2). This figure also shows the valve control relays 61 to 64 and 71 to 74 (these latter relays correspond to the box 19 of Fig. 2), and the connecting lines. The last digits 1 to 4 of these reference numbers indicate that the relay or element referred to corresponds to one of the regenerators identified by numerals 1 to 4 in Fig. 2. After each control measurement of one of the thermometers 11, 12, 13, or 14, the drop-ball instrument 16 may transmit one of 3 possible control impulses over the relays 17 to the disc 18. In other words the temperature measured will either be within the predetermined range of fluctuation within the desired normal temperature, or the temperature measured will be higher or lower than the desired temperature. Accordingly, one of the relays 31 to 34, 41 to 44 or 51 to 54 is conditioned or prepared for operation over lines 131 to 134, 141 to 144 or 151 to 154, but the switch 26, which controls the circuit including lines 55 and 58 leading to the control relays 61 to 64, 71 to 74 is still open and consequently the closing of these relays does not operate the valves. Simultaneously with the conditioning of relays 31 to 34, 41 to 44, or 51 to 54, the disc 18 is rotated, in the direction of the existing unbalance, $\frac{1}{4}$ th of its circumference, by virtue of the current impulse transmitted by the drop-ball instrument. If the temperature measurement at one of the regenerators 1 to 4 shows that the temperature of the air is lower than the normal value, one of the relays 31 to 34 will be operated and the disc 18 will be rotated in a counter-clockwise direction. If the measurement shows that the air leaving the regenerator is too hot, then one of the relays 51 to 54 is operated and the disc is turned clockwise. If the instrument measures the desired or normal value for the air temperature, then only relays 41 to 44 are operated, while the switching-disc 18 remains stationary.

Since the temperature of the air leaving the regenerators is measured toward the end of the periods of three minutes during which air flows through the regenerators, and since the movements at which the direction of flow of the oxygen and nitrogen regenerators are reversed are spaced apart from one another, the measuring of the individual regenerator temperatures takes place consecutively at equal time intervals of one and one-half minutes, so that the operation of the various relays and the rotation of the switching disc 18 on the basis of the measurements at the individual regenerators occurs consecutively.

The mean value of the individual temperatures is determined by virtue of the fact that an operation of the throttle valves 21 to 24 through the closing of the switch 26 can be effected over relays 61 to 64, or 71 to 74, and lines 221 to 224 only if all four regenerators have transmitted their measurement impulses to the relays 31 to 34, 41 to 44, 51 to 54 of the switching disc 18, and that after each 4 measurements, the switch disc 18 has a position which is the sum total of the four individual displacements. If, for example, two regenerators are too cold and two too hot, then the movements of the disc caused by the individual temperature measurements equalize one another. If three regenerators are too warm and one too cold, then the disc will be turned clockwise for two units out of its normal position.

The formation of the average temperature value, which is automatically derived by virtue of the rotation of the switching disc in response to the arrival of individual correcting impulses, furnishes the desired mean value of the regenerator temperatures and produces the following effect upon the control of the throttle valves: After all four regenerators have transmitted their impulses over the drop-ball instrument to the relays 31 to 34, 41 to 44 and 51 to 54, switch 26 is actuated; this switch closes, over lines 55 and 58 the circuits in which are located the relays 61 to 64 and lines 161 to 164 for opening the throttle valves, or the relays 71 to 74 over lines 171 to 174 for closing the throttle valves, as the case may be. It will be appreciated that not every one of the relays 31 to 34, 41 to 44 or 51 to 54 is in a condition to effect a control operation, but only those whose contactors 101 to 104, 111 to 114, or 121 to 124 are conductively connected through metallic members 81 to 84, or 91 to 94, respectively, to the operating relays. In this manner, the air supplied to those regenerators only whose temperature is different from the desired mean temperature is controlled. The following two examples are designed to illustrate this feature of the invention. Assume that the measurement of the temperature has resulted in a finding that the regenerators 1 and 3 are warmer, regenerators 2 and 4 colder, than the normal value. Thus relays 51 and 53 and 32 and 34, respectively, are conditioned for operation over lines 151, 153, 132 and 134. The distributor disc 18 assumes the position shown in the drawings, since the individual displacements have compensated each other. Thus, relays 32 and 34 are connected to relays 62 and 64 over conductors 232, 234, contact springs 102, 104 and conductors 82 and 84; also the relays 51 and 53 are connected over lines 251 and 253, contact springs 121 and 123, conductors 91 and 93 to the relays 71 and 73, so that after the determination of the mean value, all the temperature measurements initiate control operations because the temperature of all the regenerators deviates from the mean value. Therefore, after the switch 26 is closed the air supply to the regenerators 1 and 3 is reduced, by closing the throttle valves 21 and 23 a certain amount over lines 221 and 223 by the operation of relays 71 and 73 while that to regenerators 2 and 4 is increased by opening the throttle valves 22 and 24 a certain amount by means of relays 62 and 64, which transmit their impulse to the respective valves over lines 222 and 224. The impulse delivered to the valves by relays 61 to 64 over lines 221 to 224 is of opposite sign, e. g. positive, as compared to the impulse delivered over the same lines by relays 71 to 74, e. g. negative. This is necessary so that operation of relays 61 to 64 will cause an opening movement while that of relays 71 and 74 will cause a closing movement as described. To furnish such impulses the movable contactors of relays 61 to 64 may be connected to the positive pole of a battery 19 of an even number of cells while the negative pole of the battery is connected to the contactors of relays 71 to 74 and the midpoint connector of the battery is grounded. The circuits are completed by grounding one connection of each valve operating motor, the other being connected to the respective lead 221 to 224 as shown.

Assume, in another case, that all four regenerators are too cold as compared to the predetermined normal figure, for the reason, for ex-

ample, that an error was made in selecting the normal temperature. In this event, it is true that all relays 31 to 34 are brought into switching preparation by the temperature measurements, however, the switching disc was simultaneously turned counter-clockwise by four units, that is, a total of 90°, so that the conductor bars or strips 81 to 84 no longer touch contactors 101 to 104 and even after the closing of the switch 10 26, the circuit leading to the relays 61 to 64 remains open. Although the bars 91 to 94 are then touching contactors 121 to 124 and 111 to 114, the relays 51 to 54 and 41 to 44 are open so that relays 71 to 74 also remain open and no 15 change of the valves 21 to 24 is made and the distribution of air among the regenerators is not changed. Thus an error in selecting the normal temperature does not upset the distribution and the condition is to be corrected by selecting a new normal or changing the total quantity of air supplied.

In general, a regulation of the air supply to the individual regenerators is effected only in the instances given in the table below. The columns 25 of the table give the number of regenerators which find themselves in a certain state, while the letters beside the figures characterize the special state; "n" indicates that the air passing out of the regenerator is of the desired or normal temperature; "k" means that it is too cold, and "w" that it is too warm. Those regenerators to which the air supply is changed following the mean value determination are underlined.

Position of the switching disc	Displacements of the disc after four regulating measurements	Result of the regulating measurement	
		2 k 2 w	2 n 1 k 1 w 4 n
Unchanged.....	0	<u>2 k 2 w</u>	<u>2 n 1 k 1 w 4 n</u>
Number of shifts toward cold.....			
	1	<u>3 n 1 k</u>	<u>1 n 1 w 2 k</u>
	2	<u>2 n 2 k</u>	<u>1 w 3 k</u>
	3	<u>1 n 3 k</u>	
	4	<u>4 k</u>	
Number of shifts toward warm.....			
	1	<u>3 n 1 w</u>	<u>1 n 1 k 2 w</u>
	2	<u>2 n 2 w</u>	<u>1 k 3 w</u>
	3	<u>1 n 3 w</u>	
	4	<u>4 w</u>	

After the throttle valves have been regulated through switch 26 over relays 61 to 64 or 71 to 74 55 and lines 221 to 224 in the underlined instances, the disc 18 is returned to the starting position and switch 26 is opened. The switch 26 is coupled in suitable fashion with the switching machine 15 which reverses the direction of flow of the gases 60 through the regenerators.

By determining the mean value prior to a control operation, the temperature measurements of all regenerators have the same weight. That is, no consideration is given to the volume of the air which flows through the individual regenerator. In view of this, the mean value of the regenerator temperatures determined for the purpose of regulation need not agree with the effective temperature of the air leaving the regenerators. However, this does not produce operation, inasmuch as the throttle valves operated following the mean value determination are adapted to the air volume flowing through the regenerator in question, so that when they are operated, the individual 75 measurements are automatically interpreted ac-

cording to the volume of air flowing through the regenerator.

In the event the fresh gas is to be distributed to more than four regenerators, the principle of the invention may be practiced in substantially the same manner. In this event, an additional relay is inserted in each group of relays 31 to 34, 41 to 44 and 51 to 54 and an additional accompanying conductive strip is secured adjacent to each set of strips 81 to 84 and 91 to 94 for each additional regenerator. The number of displacements which position the bars 81 to 84 and 91 to 94 in the zero setting of the switching apparatus in front of the contact springs 111 to 114 is equal to one-half the number of the individual measurements, that is, when using six regenerators, three displacements, before the zero setting, and four when using eight regenerators.

It is furthermore possible with the described apparatus to separate the regulation of the fresh gas distribution to the individual regenerators into several stages. In this event, additional relays are operated by the drop-bail instrument whenever the regenerator temperatures deviate to a greater extent from the normal figure, these 20 relays thus effecting a greater change in the fresh gas volumes. The mean value determination in this case is effected in that the relays of the second stage transmit their impulses to a switching apparatus which operates in the same manner as that 25 described for the first stage.

Instead of the electrical transmission of the temperature measurement impulses and the electrical mean value determination as described above, it is possible to utilize similarly operating 35 mechanical regulation apparatus. Jet tubes, for example, may be used instead of the relays 31 to 34, 41 to 44 and 51 to 54 and the contacts 101 to 104, 111 to 114 and 121 to 124, and the contact rails 81 to 84 and 91 to 94 may then be replaced by 40 suitable openings in the switching apparatus.

Each individual control operation changes the volume of the air, so that the temperature difference between separation product and air at the cold end of the regenerator in the permanent state 45 is changed a certain amount, for example 2°. The establishment of the new permanent state following each regulation takes several reversal periods also at the lower end of the regenerator. If, therefore, a regulation at the end of each regenerator period was attempted, an excess of control or regulation would result. This difficulty may be obviated either by effecting a control operation only at intervals of from five to ten 50 reversals, or by providing a suitable feed-back. The feed-back may preferably be accomplished by electrical means, in that simultaneously with the regulating operation, the bridge formed by two thermometers 11 and 12 or 13 and 14 is so 55 adjusted by the insertion or shunting of additional resistances, that the change in the temperature difference in the state of equilibrium corresponding to one operation had already partly taken place, for example, to one-third. The feed-back is or may be cancelled at the subsequent 60 measurement of the temperature difference of the same regenerator, during which the drop-bail instrument remains in the rest position.

A satisfactory supervision of the operations and the control of the operations may be combined 70 in a simple manner with the distribution of the fresh gas volumes to the individual regenerators. For this purpose, for example, red signal lamps may be simultaneously operated with the relays 31 to 34, white lamps with the relays 41 to 44. 75

and green lamps with the relays 51 to 54. These lamps would immediately inform the supervising personnel whether or not a particular regenerator is at the normal temperature. Likewise, the 5 impulses of the relays 31 to 34, 41 to 44 or 51 to 54 can be transmitted to a multiple-recorder, whereby either the temperatures of the regenerators or the individual regulations following the mean value determinations may be recorded, as 10 desired for purposes of supervision and control.

The above-described methods of and means for automatically regulating, supervising, or controlling gas volumes flowing through regenerators by means of measuring the temperatures and regulating the deviations from the mean value, may be applied also to any case in which a volume, 15 temperature or concentration is to be controlled on the basis of a measurement of a variable, by several apparatus of the same kind which are connected in parallel or in series, whereby the total volume, the total temperature or the total concentration is to be governed from a predetermined initial value, or is to result in a certain final value. We may mention, by way of example, the case in which a plurality of air compressors of different capacity are operated in parallel and it is desired to obtain a given total 20 or final pressure with a minimum power consumption, or when all stages of a multi-stage compressor are to bear an equal load.

A further example of a possible method of regulation in accordance with the present invention consists in the control of steam withdrawal from several steam boilers operating in parallel; in the 25 event that the individual boilers show different characteristics, a simple means is afforded, according to this invention, to cause all boilers automatically to bear an equal load despite variations in the total steam withdrawal.

40. What is claimed is:

1. Method of distributing gaseous fluids supplied in constant total quantity to a plurality of heat exchange devices which includes varying automatically the amount of gas entering each 45 of said devices in accordance with the variations in temperature between the temperature of the gas discharged by said devices and an assumed normal discharge temperature.

2. In the separation of gas mixtures into their 50 components by removing heat therefrom, the method of distributing said gases to a plurality of heat exchange devices, and varying the volumes of gas entering each of said devices in inverse proportion to the temperature increment of 55 the gas discharged from said devices above a predetermined reference temperature.

3. Method as defined in claim 2, which comprises controlling the gas volumes by means electrically responsive to said temperature variations.

60. 4. Method for automatically controlling the distribution of a gaseous fluid which is to be cooled, which comprises conducting said fluid through a plurality of heat exchange devices or regenerators, individually measuring the temperature of the fluid at each of said devices, determining the mean value of said individual temperature measurements, and effecting a change in the gas supply to only those regenerators whose temperature deviates from this mean value.

70. 5. Method as defined in claim 4, which comprises determining the mean value of the individual temperature measurements by producing departures from normal of suitable compensating elements, the direction and magnitude of said departures being a function of the deviation of a

temperature control measurement from a predetermined normal figure.

6. The method of controlling the distribution of gas through heat exchange devices, which comprises determining the temperature of the gas flowing through each of said devices, computing the average temperature for the gases flowing through all of the said devices, and acting upon the gas flow of those of said devices whose gas temperature deviates from said average temper- 10

ature.

7. System for automatically controlling the distribution of a gaseous fluid to a plurality of heat exchange devices, comprising means for transmitting impulses according to the temperature variations of said devices, means for determining the mean value of said variations in temperature and for storing the net effect of said impulses responsive to said variations, said means including a rotary switching disk provided with 20 two sets of partly circular rails which are adapted to be displaced by the deviations of the individual regulating measurements from a predetermined normal value, a plurality of relays, and means for connecting said contacts to those relays only 25 which were operated by a control measurement which deviated from the said mean value.

8. System according to claim 7, characterized in that for each heat exchange device there is provided a group of relays and two contact rails 30 conductively connected to control relays, so that when the switching disk is in its neutral position all of the contact rails terminate symmetrically with respect to the relays which are operative at the normal temperature, whereas the distance 35 from one rail set to the other corresponds to as many individual displacements of the disk as there are heat exchange devices.

9. System according to claim 7, characterized by the provision of circuit preparing relays and 40 indicating devices which are operated simultaneously with the rotation of said disc.

10. System as defined in claim 7, comprising thermometers of the electrical resistance type to 45 measure the temperatures of the gases at the regenerators, a device of the cross-coil type responsive to said temperature measurements, and means for automatically recording the fluctuations or regulations of the temperatures measured 50 by said thermometers.

11. In the separation of gas mixtures into their components by removing heat therefrom, the method comprising, supplying a constant quantity of the gas to be separated, distributing said gases among a plurality of heat-exchange devices arranged in pairs, by controlling the proportionate amount of the gas entering each of said devices in accordance with the difference in temperature existing between the two devices of one pair.

12. In the separation of gas mixtures into products of separation by removing heat therefrom, the method comprising supplying a substantially constant quantity of the gas to be separated, cooling a plurality of heat-exchange devices with the products of separation, and controlling the volume of gas admitted to each of the heat-exchange devices in response to a variation in the difference in temperature between the gas mixture and the products of separation at the 65 cold end of the heat exchange device.

13. In a method of separating a gas mixture into its components at low temperature wherein the mixture is cooled by heat exchange with products of separation by means of cold accumulators 70

arranged in pairs, the steps comprising, maintaining the periods between reversals of flow through said accumulators substantially constant, and apportioning the quantity of gas mixture between the accumulators of each pair in accordance with the temperature of the mixture leaving the accumulators.

14. In a method of separating a gas mixture into its components at low temperature wherein the mixture is cooled by heat exchange with products of separation by means of cold accumulators arranged in pairs, the steps comprising, maintaining the periods between reversals of flow through said accumulators substantially constant, and reducing the proportion of gas mixture passing through one accumulator of a pair in response to a rise in temperature of the gas mixture leaving said accumulator.

15. In a method of separating a gas mixture into its components at low temperature wherein the mixture is cooled by heat exchange with products of separation by means of cold accumulators arranged in pairs, the steps comprising, maintaining the periods between reversals of flow through said accumulators substantially constant, supplying the gas mixture in substantially constant total quantity, and changing the quantity of gas mixture supplied to any one of said accumulators in response to a variation in temperature of the cold portion thereof from the mean temperature value of the cold portions of all the accumulators.

16. In a method of separating a gas mixture

into its components at low temperature wherein the mixture is cooled by heat exchange with products of separation by means of cold accumulators arranged in pairs, the steps comprising, maintaining the periods between reversals of flow through said accumulators substantially constant, supplying the gas mixture in substantially constant total quantity, controlling the amount of gas mixture admitted to each of said accumulators in response to variations in the difference in temperature between the mixture and the products of separation at the cold end of the accumulator, and regulating the distribution of the mixture among the accumulators in accordance with variations of the temperature of the cold ends thereof from a desired temperature level.

17. System for automatically controlling the distribution of a gas mixture to be cooled to a plurality of accumulators arranged in pairs comprising, means for automatically reversing the flow through said accumulators at constant time intervals, means for individually regulating the quantity of gas mixture supplied to each accumulator, means for producing intermittent impulses when the temperature of the fluid discharged from any one of said accumulators varies from a desired value, and means for causing said impulses to actuate said individual regulating means to change the quantity of gas mixture supplied to said accumulator so as to counteract said variation.
